UNITED STATES PATENT OFFICE

2,251,912

FOURDRINIER WIRE STRINGING CARRIAGE

Earl E. Berry and Lloyd Hornbostel, Beloit, Wis.,
assignors to Beloit Iron Works, Beloit, Wis.,
a corporation of Wisconsin

Original application January 6, 1938, Serial No.
183,629. Divided and this application June 28,
1939, Serial No. 281,638

9 Claims. (Cl. 242—90)

This invention relates to a carriage or truck for unreeling a Fourdrinier wire bundle into an open loop in the aisle adjacent a Fourdrinier paper making machine and more specifically relates to a wheeled carriage having clamp members rotatable about a fixed axis for receiving the ends of the spool poles of a Fourdrinier wire bundle to facilitate the unreeling of the bundle into an open loop.

This application is a division of our copending application entitled: "Fourdrinier wire stringing device and method," Serial No. 183,629, filed January 6, 1938.

Fourdrinier wires, for paper making machines, are conventionally shipped in bundles formed by inserting a pole within the loop of the wire and by wrapping the wire double around another pole outside of the loop and the inserted inside pole. The free end of the wire then receives another pole within the loop thereof.

The first pole will hereinafter be called the "inside wire spool pole" while the other pole around which the wire is wrapped will be identified as the "outside wire spool pole." The pole inserted through the free end of the wire will be referred to as the "inside wire free end pole."

The carriage, trolley or truck of this invention has revolvable clamps thereon for receiving the spool poles of a Fourdrinier wire bundle. The carriage also has overhead supports for receiving the ends of the free end pole of the Fourdrinier bundle. Receptacles are provided on the carriage for receiving additional intermediate poles inserted in the loop of the wire mounted on the carriage between the spool poles and the free end pole.

In unreeling the wire bundle from the carriage to form an open loop of the Fourdrinier wire in the aisle alongside of a paper making machine, the free end pole of the wire bundle is transferred from the overhead carriage supports to brackets on the upper ends of a pair of posts mounted in the aisle adjacent the breast roll end of the machine. One of the intermediate poles on the carriage within the loop of the wire is then transferred to brackets carried at the lower ends of said posts.

The carriage is then moved along the aisle toward the couch roll end of the machine. During this movement of the carriage the spool poles are rotated around each other while carried in the revolvable clamps of the carriage to unreel the wire. Other intermediate poles on the carriage within the loop of the wire are then trans-

ferred to overhead supports at spaced intervals above the aisle for supporting the upper run of the wire loop. The carriage may also carry additional poles outside of the loop of the wire for placing on the aisle floor to support the lower run of the loop.

When the carriage reaches the couch roll end of the machine, the inside wire pole of the spool poles is transferred from the revolvable clamps on the carriage to the upper brackets of another pair of posts mounted in the aisle. An intermediate pole on the carriage within the loop of the wire is next transferred to lower brackets on the same posts. The wire is thus disposed in an open loop in the aisle adjacent the table structure of the machine.

The table structure of the paper machine can then be laterally removed into the open loop of the wire according to known methods such as, 20 for example, on laterally extensible rails as disclosed in the Earl E. Berry Patent No. 2,003,103 dated May 28, 1935.

It is, then, an object of this invention to provide a carriage for unreeling a Fourdrinier wire 25 bundle into an open wire loop adapted to receive the removable table structure of a paper making machine therein.

A further object of the invention is to provide a carriage for facilitating the stringing of a 30 Fourdrinier wire into an open loop in the aisle alongside of a paper making machine.

Another object of the invention is to provide 35 a Fourdrinier wire stringing carriage having clamps rotatably mounted therein about a fixed axis for receiving the ends of the spool poles of a Fourdrinier wire bundle.

A specific object of the invention is to provide 40 a Fourdrinier wire stringing carriage mounted on steerable wheels and having spaced opposed clamp members rotatably mounted about fixed axes.

Other and further objects of the invention will 45 become apparent to those skilled in the art from the following detailed description of the annexed sheets of drawings which disclose a preferred embodiment of the invention.

On the drawings:

50 Figure 1 is an end elevational view of a Fourdrinier wire bundle as it is wrapped by the manufacturer.

Figure 2 is a side elevational view of a carriage, trolley or truck according to this invention for unreeling the wire bundle into an open loop.

Figure 3 is a broken front elevational view of the carriage shown in Figure 2.

Figure 4 is a fragmentary cross-sectional view taken along the line IV—IV of Figure 3.

Figure 5 is a fragmentary diagrammatic side elevational view illustrating the manner in which the carriage of this invention is utilized to unreel a Fourdrinier wire bundle into an open loop.

As shown on the drawings:

In Figure 1 the reference numeral 10 designates generally a Fourdrinier wire bundle as the same is shipped by the wire manufacturers. The bundle 10 comprises an inside wire pole "B" disposed in one end of the endless Fourdrinier wire "F.W." The wire is then wrapped around the inside wire pole B and an outside wire pole C. The other end of the endless wire receives the inside wire pole A therethrough. Since the poles A and B are the only poles inside the loop of the wire they are called inside wire poles. The poles B and C, however, form the spool around which the wire bundle 10 is formed and a pole A merely protects the free end of the wire.

As shown in Figures 2 and 3 the reference numeral 11 designates generally a carriage or trolley for unreeling the wire bundle 10 into an open loop adapted to receive the table structure of a paper making machine therein.

The carriage 11 consists of side frame members 12 joined together by transverse tubes 13. The tubes 13 are held in the frame members 12 by means of bolts such as 14.

The shanks 15 of casters 16 are swivelly mounted through the ends of the tubes 13 in each frame member 12, thereby providing four swivelly mounted caster wheels 16 for the carriage.

The casters 16 have gears 17 secured around the shanks thereof meshing with worms secured on shafts 18 mounted under each frame 12 in brackets 19 and 20. Cranks 21 are secured on the front ends of the shafts 18 for manual rotation of the shafts to turn the casters and thus steer the carriage.

The frames 12 have upwardly extending pedestal portions 22 at the front end of the carriage. Bearing housings 23 are bolted on top of the pedestals 22 and the shafts 24 of clamp members 25 are rotatively mounted on bearings (not shown) in the bearing housings 23.

The ends of the clamp members 25 are grooved as at 26 (Fig. 3) for receiving therein the shanks of bolts 27 pivotally mounted on the ends of yoke members 28 cooperating with the clamp members 25. Nuts 27a can be threaded on the ends of the bolts 27 for drawing the yokes 28 towards the members 25.

The members 25 and 28 are thus revolvable in the bearing housings 23.

As best shown in Figures 3 and 4, the bearing housings 23 are each provided with an inwardly extending lip 23a for supporting a brake band such as 30 disposed around each shaft 24 of a member 25.

As shown in Figure 4 one end of the brake band 30 is secured to a bracket 31 extending through the lip 23a and held in fixed position thereon by means of nuts 32 engaging the opposite faces of the lip.

The other end of the brake band 30 is secured to a bracket 33 having a threaded shank portion 34 extending through the lip 23a and receiving in threaded relation thereon a thumb nut 35 adapted to abut the top face of the lip 23a. Manipulation of the nut 35 thus controls the frictional en-

gagement between the brake band 30 and the shaft 24.

As shown in Figure 3, a brake 30 is provided for each shaft 24.

5 As best shown in Figure 2, the bundle 10 is mounted on the carriage 11 by placing the ends of the spool poles B and C on the clamp members 25. These members can be held in horizontal position for receiving the wire poles by tightening the brake bands 30. The yoke members 28 are then secured on the members 25 to clamp the spool poles in position.

When the bundle 10 has thus been assembled on the carriage 11, the free end pole A may be moved down to supports such as 36 formed on the frame members 12 behind the pedestals 22.

15 Vertical posts 37 and 38 are mounted on the frames 12 in spaced relation from the back end of the carriage. Pole receiving brackets 39 are secured at the tops of the posts 37 and 38.

20 A bracket 40 is clamped on the post 37 in spaced relation from the top thereof. The bracket 40 has an inwardly and downwardly extending arm portion 41 and an outwardly and upwardly extending arm portion 42 as best shown in Figure 3. Concave guide rollers 43 and 44 are rotatively carried on the ends of the arms 41 and 42 respectively around axle pins 45 projecting horizontally from the arms toward the rear of the carriage. The arrangement of the arms is such to mount the rollers for receiving a pole therebetween and for holding the pole transversely across the carriage in a cantilevered position. However, the free end of the pole can be 35 tilted upward for a purpose to be hereinafter more fully described.

25 Pins or posts such as 46 are mounted on the frames 12 in spaced parallel relation behind the posts 37 and 38 to define with the posts 37 and 38 a pole receptacle 47.

30 A second set of pins or posts 48 are mounted on the back ends of the frames 12 to define with the posts 46 a second pole receptacle 49.

35 Brackets such as 50 are mounted under the frames 12 for supporting wire poles for a purpose to be hereinafter described.

40 A tray 51 is mounted on the front tube 13 in the central portion of the carriage. The tray 51 supports wire pole blocks 52 for a purpose to be hereinafter described.

45 In charging the carriage for unreeling a Fourdrinier wire bundle into an open loop, the wire bundle is mounted on the clamps 25 as explained above. Wire pole A is then moved from the support 36 to the brackets 39 at the top of the posts 37 and 38. During this positioning of the wire pole A, the wire F. W. is unreeled from the spool poles B and C to form an open loop between the clamps 25 and the pole A as best shown in Figure 2. Wire poles D, E and F are then inserted through the loop of the wire in the receptacle 49 provided on the carriage. Additional wire poles G, H and J are also inserted through the loop of the wire and seated in the receptacle 47 of the carriage.

50 Outside wire poles K, L and M are mounted on the brackets 50 of the carriage and the pole blocks 52 are placed in the tray 51.

55 The carriage is then charged for unreeling the Fourdrinier wire into an open loop adjacent the table structure of a Fourdrinier paper making machine.

60 As shown in Figure 5, an aisle floor 60 along-side of a paper making machine (not shown) has vertical posts such as 66 mounted thereon adja-

cent the breast roll end of a paper making machine. The posts 66 are spaced apart from each other for a sufficient distance to receive the carriage 11 therebetween.

The posts 66 have lower pole-receiving brackets 67 near the bottoms thereof and upper pole-receiving brackets 68 at the tops thereof. The brackets 67 and 68 face the couch roll end of the machine.

With the carriage 11 charged as shown in Figures 2 and 7, the same is moved along the aisle 60 between the posts 66. The wire pole A is then transferred from the bracket 39 on the carriage posts 37 and 38 into the brackets 68 on the aisle posts 66.

The intermediate pole D, which is the top pole in the receptacle 49 of the carriage, is then transferred from the receptacle into the bracket 67 of the aisle posts 66. The carriage is then moved along the aisle while unreeling the forming wire F. W. from the spool poles B and C by rotation of the clamps 25.

The next roll E in the receptacle 49 of the carriage is removed from the receptacle and suspended between the rollers 43 and 45 on the carriage post 37 to hold the pole in a cantilever position. The free end of the pole is then tilted upwardly to engage a cable 70 suspended from the ceiling (not shown). The other end of the pole is then removed from the rollers 43 and 45 and mounted in a complementary cable to suspend the pole horizontally from the ceiling and hold the upper run of the wire F. W. in a substantially horizontal position level with the bracket 68 on the posts 66.

A pair of pole blocks 52 are then removed from the tray 51 on the carriage and are mounted on the aisle floor. The pole K is then removed from the brackets 50 on the carriage and mounted on the pole blocks 52 to hold the lower run of the wire F. W. above the aisle floor.

In a similar manner the intermediate poles F and G are removed from the carriage and suspended from overhead cables to hold up the upper run of the wire F. W. Likewise, the poles L and M are removed from the carriage and mounted on pole blocks on the aisle floor under the under run of the wire to hold the wire above the floor.

An additional pair of posts such as 66 are mounted on the aisle floor at the couch roll end of the machine and the remaining poles H and J on the carriage can be mounted in double lower post brackets (not shown) on the posts. The inside wire spool pole B is transferred from the clamps 25 of the carriage to the upper bracket of the posts and the outside wire spool poles D can be transferred to the supports 36 of the carriage.

The wire F. W. is thus disposed in an open loop in the aisle 60 adjacent the removable table structure of a Fourdrinier paper making machine. The upper run of the loop can be raised as shown in dotted lines in Figure 5 by shortening the cables 70 and the removable table structure of the machine can be readily moved into the open loop for receiving the wire therearound.

From the above description it should be understood that this invention provides for the unreeling of a Fourdrinier wire from a bundle into an open loop in the aisle alongside of a paper making machine. The table structure of the paper making machine can then be moved into the open loop of the wire. The carriage of this

invention provides for the replacing of a new Fourdrinier wire on Fourdrinier paper making machines having removable table structures without damaging the wire and without requiring skilled technicians to effect the wire change.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. A carriage for stringing a Fourdrinier wire into an open loop which comprises a chassis, wheels movably supporting said chassis from the ground, spaced opposed clamps revolvably mounted in stationary bearings on opposite sides of said chassis and adapted to receive the ends of spool poles having a Fourdrinier wire wrapped therearound to form a Fourdrinier wire bundle, a pair of spaced posts extending upward from the chassis, and pole supports at the top of said posts adapted to receive the ends of the wire pole through the free end of the Fourdrinier wire bundle.
2. A carriage for stringing a Fourdrinier wire into an open loop which comprises a chassis, wheels supporting said chassis from the ground, fixed bearing housing on opposed sides of the chassis, spaced opposed clamp members having axles rotatably mounted in said bearing housings, said clamps adapted to receive the ends of spool poles having a Fourdrinier wire wrapped therearound to form a Fourdrinier wire bundle, a pair of spaced vertical posts at opposite sides of said chassis, pole supports at the tops of said posts adapted to receive a wire pole therein, and means defining receptacles on said chassis for additional wire poles.
3. A carriage for stringing a Fourdrinier wire into an open loop which comprises a pair of side frame members, transverse members holding the frame members in spaced parallel relation to form a rigid chassis, wheels movably supporting said chassis from the ground, said side frame members each carrying aligned bearing housings, clamp members rotatably mounted in each of said bearing housings adapted to receive the ends of spool poles having a Fourdrinier wire wrapped therearound to form a Fourdrinier wire bundle, vertical posts extending upward from each of said frame members, pole supports at the tops of said posts for receiving therein the ends of the wire pole through the free end of a Fourdrinier wire bundle, additional posts extending upward from said side frames to define pole receptacles on said chassis, and means for steering said wheels.
4. A carriage for stringing a Fourdrinier wire into an open loop which comprises a pair of spaced opposed side frame members, tubes extending transversely between said frame members and seated at their ends therein, casters having shanks swivelly mounted in said side frame members, caster wheels rotatably mounted on said casters, shafts rotatably carried beneath each of said frame members and extending adjacent the casters, crank arms on the front ends of the shafts, worm and gear connections between the casters and the shafts whereby a rotation of the crank arms will swivel the casters and wheels, and clamp members rotatably carried on said frames adapted to receive therein the ends of spool poles having a Fourdrinier wire wrapped

therearound to form a Fourdrinier wire bundle. 5. A carriage for unreeling a Fourdrinier wire bundle into an open wire loop which comprises a chassis movably supported from the ground, means for steering said chassis, a vertical post extending upwardly from said chassis, a bracket secured on said post having an inwardly and downwardly extending arm and an upwardly and outwardly extending arm, and rollers horizontally carried on the ends of said arm whereby a wire pole can be inserted between the rollers and supported by the bracket in a cantilever position.

6. The method of unreeling into an open loop a Fourdrinier wire bundle having a pair of spool poles with an endless Fourdrinier wire wrapped therearound, one of said spool poles being inside of the wire, the other of said spool poles being outside of the wire and a free end pole inside the wire at the outer end of the bundle, which comprises clamping the ends of the spool poles of the bundle in rotatable supports, supporting the free end pole of the bundle in spaced relation above the clamped spool poles, inserting a plurality of intermediate poles into the loop of the wire between the free end pole and the clamped spool poles, transferring the free end pole to fixed supports, transferring an intermediate pole to fixed supports spaced below the free end pole, rotating the clamped spool poles around each other to unwind the wire while moving the same away from the fixed supports, progressively suspending other intermediate poles at spaced intervals from the fixed supports to support the upper run of the wire, continuing said rotation and moving of the spool poles until the bundle is unwound, transferring the inside wire spool pole to fixed supports, and transferring an intermediate pole to fixed supports in spaced relation from the inside wire spool pole.

7. The method of unreeling into an open loop a Fourdrinier wire bundle having a pair of spool poles with an endless Fourdrinier wire wrapped therearound, one of said spool poles being inside of the wire, the other of said spool poles being outside of the wire and a free end pole inside the wire at the outer end of the bundle, in the aisle alongside the table structure of a Fourdrinier paper making machine which comprises, mount-

ing the ends of the spool poles of the bundle in spaced opposed securing members on a mobile carriage, supporting the free end pole of bundle on said carriage in spaced relation from the mounted spool poles, mounting a plurality of intermediate poles on the carriage in the loop of the wire between the spool poles and the free end pole, transferring the free end pole and an intermediate pole from the carriage to pairs of superimposed fixed supports in the aisle, rotating the spool poles around each other about a fixed axis while moving the carriage away from the transferred free end pole, and progressively transferring other intermediate poles from the carriage to overhead supports as the carriage reaches predetermined spaced distances from the free end pole to suspend the upper run of the wire.

8. A carriage for unreeling a Fourdrinier wire bundle to form an open wire loop which comprises a chassis, wheels and wheel mountings supporting the chassis from the ground, bearing housings mounted on said chassis in spaced opposed relation on opposite sides thereof, said bearing housings being independent of the wheel mountings, clamp members rotatably mounted in said bearing housings independently of the wheels and adapted to receive the ends of spool poles having a Fourdrinier wire wrapped therearound to form a Fourdrinier wire bundle, and supports on said chassis for receiving additional wire poles thereon.

9. In a carriage for unreeling a Fourdrinier wire bundle, a chassis, wheels and wheel mountings supporting the chassis from the ground, a pair of spaced opposed fixed bearing housings on said chassis, said bearing housings being independent of the wheel mountings, clamp members each rotatably supported from a bearing housing independently of the wheels and adapted to receive the ends of spool poles having a Fourdrinier wire wrapped therearound to form a Fourdrinier wire bundle, and a brake device co-operating with each of said clamp members for imparting resistance to the rotation of said clamp members.

EARL E. BERRY.
LLOYD HORNBOSTEL.
